UNITED STATES PATENT OFFICE

100,831

DESIGN FOR A CASING FOR A TYPOGRAPHICAL MACHINE

Herbert Rosengren, Rockford, Ill., assignor to Intertype Corporation, Brooklyn, N. Y., a corporation of New York

Application May 29, 1936, Serial No. 62,911

Term of patent 14 years

To all whom it may concern:

Be it known that I, Herbert Rosengren, a citizen of the United States, residing at Rockford, in the county of Winnebago, State of Illinois, have invented a new, original, and ornamental Design for a Casing for a Typographical Machine, of which the following is a specification, reference being had to the accompanying drawings, forming part thereof.

In the accompanying drawings:

Fig. 1 is a perspective view of the front of a casing for a typographical machine showing my new design; and

Fig. 2 is a perspective view showing the rear of said casing.

I claim:

The ornamental design for a casing for a typographical machine, substantially as shown.

HERBERT ROSENGREN.
